UNITED STATES PATENT OFFICE.

WILLIAM S. KAISER, OF MILWAUKEE, WISCONSIN.

DESIGN FOR A DOLL.

Application filed August 10, 1922. Serial No. 3,340. Term of patent 3½ years.

To all whom it may concern:

Be it known that I, WILLIAM S. KAISER, a citizen of the United States, residing at Milwaukee, in the county of Milwaukee and State of Wisconsin, have invented a new, original, and ornamental Design for Dolls, of which the following is a specification, reference being had to the accompanying drawings, forming a part thereof.

In the drawings;

I claim:

The ornamental design for a doll, as shown.

WILLIAM S. KAISER.
